ENGINE AIR-COMPRESSOR.

1,381,133.

Specification of Letters Patent. Patented June 14, 1921.

Application filed December 18, 1917. Serial No. 207,767.

To all whom it may concern:

Be it known that I, JAKOB MÜLLER, a citizen of the Republic of Switzerland, residing at Veltheim, Switzerland, have invented the 5 following described Improvements in Engine Air-Compressors.

The invention relates to the structure of air compressors such as used for compressing the fuel injection air in certain types of 10 internal combustion engines and is more especially concerned with the mounting of the piston pin of multiple stage compressor apparatus having stepped pistons, whereby certain advantages are attained which are 15 specially desirable in combustion engines for marine propulsion, all as will be hereinafter made apparent to those skilled in this art.

Referring to the drawings—

Figure 1 is a vertical section of a three-stage air compressor as applied to an engine, and having stepped pistons and incorporating the present invention. The usual compressor valves and interconnecting passages are omitted from this figure, for convenience, and inasmuch as their structure and relation forms no part of the invention.

Fig. 2 is a top plan of the piston part of greatest area; and

Fig. 3 is an axial section through a part 30 of the piston.

In Fig. 1 the cylinder structures designated 1 and 2 surmount the crank case 3 which may be a part of the crank case of the combustion engine on which the compressor is used, and the stepped piston structures 4 and 5 in said cylinders are trunk pistons operated by the connecting rod 6 from a crank shaft 7 which latter may be the main crank shaft of the engine. Certain 35 limitations in respect to the over-all height of marine engines, particularly submarine engines, prescribe a very short distance of separation between the lower end of the cylinder structure and the engine crank shaft, 40 which fact makes it desirable that the connecting rod shall extend upwardly into the piston trunk as far as possible in order that it may have a maximum length under the conditions stated and thereby give a minimum 45 side thrust on the piston when in action. To this and other ends the piston pin 8 of the connecting rod 6 is mounted, not in the side wall or trunk of the piston 5 as in the common design of trunk piston, but 50 in a separate member 9 centrally bolted to

the underside of the face or end wall of the piston 5 at the junction of the large and small diameters of the piston structure. This separate member desirably takes the form of a short cylindrical body with an 60 inturned attachment flange 10 at its upper end and it constitutes what may be called a false piston trunk, being spaced from the wall of the trunk proper so that it has no contact with the cylinder. At its lower end 65 this false trunk bears upon, but is not attached to the piston trunk proper, through the intervention of a spacing flange ring 11 which ring may be secured either to the false or the proper trunk as will be evident 70 but is here shown as formed integrally with the proper trunk. The piston pin 8 is fitted and secured to the false trunk in the same manner as is customary with piston pins directly mounted in trunk pistons. That is to 75 say, it is mounted in the bosses 12 which are formed integrally with the false trunk. Inasmuch as the false trunk is of less diameter than the trunk proper in which it is contained, it will be apparent that the piston 80 pin 8 is correspondingly shorter than would otherwise be necessary and is hence lighter. At the same time the trunk wall of the piston 5 may be cast of uniform or regular 85 sections throughout; it requires no reinforcing ribbing since it has no bearing bosses, such as 12, and it is not pierced by the piston pin, which latter fact enables the said pin to be located as close to the piston face as the necessary clearance for the connecting 90 rod head will permit, without tending to restrict the number of packing or piston rings 13 or to produce a path of air leakage through the piston pin bearing. The length of the connecting rod may thus be increased 95 to a maximum consistent with the dimensions of the other parts and adequate head room may be provided within the crank case. The high pressure piston 4 is hollow and its interior opens into the false trunk and is 100 utilized as clearance for the head of the connecting rod.

Through its connection to the piston face and its lateral bearing on the flange ring 11, the false trunk distributes the lateral thrust 105 of the connecting rod to the trunk proper and imparts the longitudinal thrust directly to the center of the face wall of the piston 5 and directly in line with the high pressure, smaller diameter, piston member 4. The lat- 110

ter is centrally attached to the opposite side of the face wall of piston 5 by means of six double ended screw studs 14, screwed into the flange and projecting through the face 5 wall of piston 5. The castellated nuts 15, counter-sunk in the base flange of piston 4, are threaded onto the upper ends of these studs and thereby clamp all three parts rigidly and securely together and in leak- 10 proof manner. The nuts 15 are accessible from the side, on removal of the high pressure cylinder structure 1, and when un-screwed permit an easy and very convenient withdrawal of the false trunk or the large 15 piston, the false trunk may be removed while still connected to the connecting rod 6 and thereby the dismantling of the compressor is greatly facilitated.

Claims.

- 20 1. In an air compressor, the combination with a stepped trunk piston and the operating connecting rod thereof, of a connection member located centrally of the piston structure at the junction of the large and small 25 diameters thereof and forming the support for the piston pin, and means accessible from the cylinder head side of said trunk piston for detachably securing said connection member thereto.
- 30 2. In an air compressor, having a stepped trunk piston structure, the combination with the connecting rod of said structure, of a false piston trunk secured to the piston structure at the junction of the large and 35 small diameters thereof and occupying the portion of larger diameter.
- 35 3. In an air compressor, having a stepped trunk piston, the combination with the connecting rod of said piston, of a false piston 40 trunk secured to the piston structure at the junction of the large and small diameters

thereof and having a spaced lateral bearing on said structure adapted to distribute the side thrust of the connecting rod thereto.

4. In an air compressor, the combination 45 with a trunk piston and the connecting rod thereof, of a false trunk within the piston trunk carrying the piston pin for the connecting rod and adapted to distribute side thrust of the connecting rod to said piston trunk, the false trunk being spaced from the walls of the latter adjacent the ends of the piston pin.

5. In an air compressor, the combination 50 with a trunk piston and connecting rod thereof, of a false trunk detachably secured to the central region of the end wall of said piston and entirely inclosed therein and laterally spaced therefrom, the false trunk carrying the piston pin for said connecting 55 rod in a part thereof laterally spaced from the piston walls.

6. In an air compressor, the combination 60 with a stepped trunk piston, the large and small diameter portions whereof are formed as separate parts, of a false trunk 65 contained within the part of larger diameter and carrying the piston pin and means for securing the said parts of large and small diameters together and to said false trunk.

7. In a device of the class described, the combination with a trunk piston and connecting rod thereof, of a false trunk located centrally in the trunk piston and detachably secured at its ends to the latter, the 75 false trunk between its ends being laterally spaced from the walls of the trunk piston and in such laterally spaced portion carrying the piston pin for said connecting rod.

In testimony whereof I have signed this 80 specification.

JAKOB MÜLLER.
